RETRACTABLE HANDLE TYPE CLOSURE
LOCK

Albert J. Leonard, Sr., Glendale, Calif.

Application August 2, 1948, Serial No. 42,058

4 Claims. (Cl. 292—1)

1

This invention relates generally to the art of locks and latches, and more particularly to locks of the type embodying an operating member or handle for the locking element, which is movable from an operating position wherein it is accessible for manipulation to unlock the locking element and hence open the closure with which it is associated, to a non-operating position wherein the handle may be substantially flush with the exterior surface of the closure such as an automobile door, so as to prevent unauthorized persons from tampering with the handle to force the lock, as well as to enhance the streamlined appearance of the vehicle and to eliminate dangerous projecting handles.

An object of my invention is to provide a lock of this type which is structurally characterized by means enabling the locking element to be unlocked, or the operating member moved to non-operating position according as a single actuator is moved to respectively different positions, all so that with the lock applied to the door of an automobile, for example, the lock bolt and the retractable outside handle of the door may be selectively operated by a single inside actuator or handle, to respectively retract the bolt and move the outside handle to its non-operating position substantially flush with the exterior surface of the door, whereby to materially simplify the construction as well as the operation of the lock.

Another object of my invention is to provide a lock having the important feature of a single inside actuating handle as above described, whose simple and compact construction enables it to be installed in doors of automobiles of the most modern design, whose door frames are extremely narrow to provide for vertically slidable windows of maximum width to attain increased visibility, all while retaining in the lock the essential qualities of durability, freedom from servicing, and simplicity of installation by assembly line production methods.

With these and other objects in view, my invention resides in the combinations, arrangements and functional relationships of elements as set forth in the following specification and particularly pointed out in the appended claims.

In the accompanying drawings,

Figure 1 is a vertical longitudinal sectional view taken on the line 1—1 of Figure 2, and showing one embodiment of my invention applied to an automobile door;

Figure 2 is a horizontal sectional view taken on the line 2—2 of Figure 1;

2

Figures 3, 4 and 5 are enlarged fragmentary sectional views taken on the lines 3—3, 4—4 and 5—5, respectively, of Figure 1;

Figure 6 is a detail sectional view taken on the line 6—6 of Figure 5;

Figure 7 is a view in end elevation, of a latching device for the outside retractable handle; and

Figure 8 is a fragmentary sectional view taken on the line 8—8 of Figure 7.

Referring specifically to the drawings, my invention, for the purpose of illustration, is shown installed in a hollow, sheet metal hinged door D of the type used on automobiles, and having a vertically slidable window indicated in broken lines at W in Figure 2.

My invention comprises a support in the form of a metal plate 10 secured in the door D at the lock stile 11 thereof in any suitable manner, with the lock stile having an opening in which works a locking element or bolt 12 having a longitudinal slot 13 receiving headed studs 14 on the plate 10 to mount the bolt for reciprocating movement. A spring 15 mounted on the plate 10, engages the bolt 12 to urge same to its projected position for latching engagement with a keeper 17 on the jamb 18.

A tubular shaft 20 is provided at one end with a journal flange 21 mounted in an arcuate bearing 22 (Figure 1) secured to the plate 10 by screws 23. Secured to the flange 21 by screws 24 is the flange 25 of a journal member 26 received in an opening of the plate 10 to form an additional bearing co-acting with the bearing 22 to rotatably mount the shaft 20 on the plate. The bolt 12 has a lug 30 engaged by an arm 31 on the flange 21 for co-action with the arm under the action of the spring 15 in urging the shaft 20 rotatably to the extreme position shown.

An outside operating member in the form of a lever handle 40, has a long hub 41 telescopically receiving the shaft 20. A pin 44 extends diametrically through longitudinal slots 45 in the shaft and is anchored at its ends in the hub 41 to operatively connect the shaft to the handle 40 for rotation by the latter, yet enable the handle to be moved axially of the shaft to occupy the operating and non-operating positions shown respectively, in full and broken lines in Figure 2.

The hub 41 of the handle 40 has bearing engagement with a bearing member 46 supported in the bottom wall 47 of a recess 48 formed in the outer wall 49 of the door D and shaped to receive the handle when the latter is moved to its non-operating position so as to be substantially flush with the exterior surface of the door.

Latch dogs 50 are reciprocably mounted in radial slots 51 in the flange 21 of the shaft 20 (Figure 6) and are urged towards each other to the latching position shown in this figure, by a U-shaped wire spring 52 mounted between the flanges 21 and 25 and having its free ends seating in notches 54 in the dogs. In the latching position of the dogs 50, their beveled inner ends 55 project into the bore of the shaft 20 so as to be disposed in the path of axial movement of an annular keeper flange 56 formed on one end of a keeper member 57 which is telescopically received in a tubular releasing member 58, which latter is guided in the bore of the shaft 20. The keeper member 57 is rigidly connected by the pin 44 to the handle 40 for unitary movement with the latter, and the flange 56 of the keeper member is adapted to co-act with the beveled surfaces 55 of the dogs 50 in moving the latter against the spring 52 sufficiently for the keeper flange 56 to pass the dogs and be latched thereto as shown in Figure 5, so as to releasably retain the handle 40 in its non-operating position shown in this figure.

The releasing member 58 has longitudinal slots 60 through which the pin 44 passes so as to permit a limited axial movement of the releasing member relative to the keeper member 57. A shank 62 on the outer end of the releasing member 58 passes through a cap 63 on the outer end of the shaft 20, and is provided with a push button 64 slidably mounted in a bore 65 of the handle 40. A coil spring 66 on the shank 62 co-acts with the cap 63 and with the push button 64 in urging the releasing member 58 axially outward to the projected position shown in Figure 5, and wherein the button is accessible for depressing, in a shallow recess 67 in the outer face of the handle 40.

An inside operating member in the form of a lever handle constitutes a single actuator 70 for selective actuation of the bolt 12 and outside handle 40. Through the engagement of lug 30 with arm 31 the bolt 12 may also be retracted by operation of the handle 40. The actuator 70 is fixed to the outer end of a pin 71 journaled in a bearing 72 on a plate 73 secured to the inner wall of the door D in any suitable manner. An arm 74 is fixed intermediate its ends to the inner end of the pin 71, and one end of the arm co-acts with springs 75 and 76 on the plate 73 to urge the actuator 70 to the position designated A in Figure 1, which is intermediate the two extreme positions of the actuator which are respectively designated B and C in this figure.

Pivotedly connected at 77 to the other end of the arm 74 is one end of a link 78, the other end of which latter is pivotedly connected by a pin 79 to a generally U-shaped cam lever 80 pivotedly mounted by a pin 81 on a bracket 82 secured to the plate 10. The pivot pin 79 is provided with a head 79a spaced from the lever 80 to receive the tail end 83 of the bolt 12 provided with a hook 84 with which the pin 79 co-acts to retract the bolt independently of the outside handle 40, in response to movement of the actuator 70 from its intermediate position A to its extreme position B, yet permit the bolt to be retracted by the outside handle 40 without moving the actuator from its intermediate position.

Also pivotedly mounted on the bracket 82 by means of a pin 85, is a shifting member or yoke lever 86 having rollers 87 working in an annular groove 88 in the hub 41 of the outside handle 40. A spring 90 co-acts with the lever 86 to urge

the handle 40 axially to its operating position shown in full lines in Figure 2.

The cam lever 80 is provided with a cam 91 having a cam surface 92 which is obliquely disposed with respect to the plane of movement of the lever, for wiping co-action with the beveled surface 93 on the shifting member 86 in moving the latter from the position shown in full lines in Figure 2 to the position shown in Figure 5, in response to movement of the actuator 70 from its intermediate position A to its other extreme position C, so as to cause the outside handle 40 to be moved by the shifting member 86 to its non-operating position shown in Figure 5.

Upon reaching this position, the handle 40 will be releasably retained therein by the automatic latching of the keeper member 57 by the dogs 50 which snap behind the keeper flange 56. To release the handle 40, it is only necessary to depress the push button 64 so as to spread the dogs 50 and free the handle for axial movement to its operating position by the spring 90.

From the foregoing description, it will be manifest that the actuator 70 provides a means common to both the bolt 12 and the handle 40 by which selective operation thereof may be effected in response to movement of the actuator to one position or another, and without interfering with actuation of the bolt directly by rotating the handle 40, or movement of the handle axially to its non-operating position by exerting manual pressure directly against the handle. Furthermore, it will be understood that the term "bolt" for the part 12 is to be broadly construed in the claims as any locking element and whether of the translatory, rotary, or a combination of these types.

I claim:

1. In locking mechanism for closures, a bolt; an operating member for the bolt; means mounting said member for rotation and for movement axially to occupy operating and non-operating positions; means urging said member to operating position; an actuator; means mounting said actuator for movement in opposite directions from an intermediate position; means operatively connecting said operating member to the bolt to retract same in response to rotational movement of said operating member; means operatively connecting said actuator to said bolt to retract same in response to movement of the actuator in one direction from said intermediate position; means operatively connecting said actuator to said operating member to move same axially to its non-operating position in response to movement of the actuator in the opposite direction from said intermediate position; means for releasably retaining said operating member in non-operating position; and means urging said actuator to said intermediate position from either displaced or extreme position thereof.
2. In locking mechanism for closures, a latch-actuating tubular rock shaft having a journal at one end; a bearing co-acting with said journal and adapted to mount said rock shaft in a closure for oscillatory movement about a fixed axis; an operating member having a hub telescopically receiving the other end of said rock shaft, and adapted to be journaled in the closure; means co-acting with said rock shaft and hub to operatively connect them for rotational movement of the shaft by the member, yet render the latter independently movable axially to occupy operating and non-operating positions; means co-acting with said hub to urge the operating

member to operating position; latch dogs mounted in said shaft and urged to latching position wherein they project into the bore of the shaft; a keeper member working in said shaft and connected to said operating member for axial movement by the latter into latching engagement with said dogs to latch the operating member in non-operating position; a tubular releasing member receiving said keeper member and guided axially in the bore of said shaft; and means connected to said releasing member and operable from a location at the hub of said operating member to move said dogs to non-latching position so as to free the operating member for movement by said urging means to operating position.

3. In locking mechanism for closures, a latch-actuating tubular rock shaft having a journal at one end; a bearing co-acting with said journal and adapted to mount said rock shaft in a closure for oscillatory movement about a fixed axis; an operating member having a hub telescopically receiving the other end of said rock shaft, and adapted to be journaled in the closure; said shaft having longitudinal slots; a pin supported diametrically in the hub of the operating member and passing through said slots to operatively connect the shaft and member for rotation as a unit, yet rendering the member independently movable axially to occupy operating and non-operating positions; means urging the operating member to operating position; latching means including a keeper member in said shaft, through which said pin passes to connect the keeper member to the operating member for axial movement by the latter to latch the operating member in non-operating position; and means operable from a location at the hub of said operating member and including a releasing member receiving said keeper member and freely passing said pin, by which the operating member can be released from the latching means for movement by said urging means to non-latching position.

4. In locking mechanism for closures, a latch-actuating tubular rock shaft having a journal

at one end; a bearing co-acting with said journal and adapted to mount said rock shaft in a closure for oscillatory movement about a fixed axis; an operating member having a hub telescopically receiving the other end of said rock shaft, and adapted to be journaled in the closure; said shaft having longitudinal slots; a pin supported diametrically in the hub of the operating member and passing through said slots to operatively connect the shaft and member for rotation as a unit, yet render the member independently movable axially to occupy operating and non-operating positions; means urging the operating member to operating position; latch dogs mounted in said shaft and urged to latching position wherein they project into the bore of said shaft; a keeper member in said shaft, through which said pin passes to connect the keeper member to the operating member for axial movement by the latter into latching engagement with said dogs so as to releasably retain the operating member in non-operating position; a push button mounted in said hub for movement axially thereof; and a tubular releasing member connected to said push button and receiving said keeper member; said releasing member being guided in said shaft and having longitudinal slots through which said pin passes to render the releasing member free for axial movement relative to the keeper member in response to depression of said button, so as to enable the releasing member to move said dogs clear of the keeper member and free the operating member for movement by said urging means to operating position.
